UNITED STATES PATENT OFFICE.

FRANK H. AHL, OF NEW YORK, N. Y.

TOBACCO-STEMMING DEVICE.

Application filed November 6, 1923. Serial No. 673,170.

To all whom it may concern:

Be it known that I, FRANK H. AHL, residing in the city of New York, county of New York, and State of New York, and a citizen of the United States, have invented certain new and useful Improvements in Tobacco-Stemming Devices, of which the following is a specification, reference being had to the accompanying drawings, forming 10 a part thereof.

My invention relates to tobacco leaves stripping or stemming machines, that is, a machine adapted to strip the laminæ of a leaf of tobacco from the stem and has for 15 its object to provide a machine with means adapted to carry and feed tobacco leaves to a mechanism adapted to remove each leaf from the feeder or carrier and to separate the stem from the laminæ. A further object 20 of my invention is a stripping or stemming machine provided with means adapted to prevent unstripped leaves from getting in among the stripped leaves. A further object is a machine provided with means 25 adapted to unfold or to spread out and straighten the stripped laminæ as they are being stripped from their stems. A still further object is a machine adapted to strip tobacco leaves and to carry the stripped 30 laminæ away from the stems.

With the objects above indicated and other objects hereinafter described in view, my invention consists in the construction and combination of elements hereinafter 35 described and claimed.

Referring to the drawings:

Figure 1 is a front elevation view of the machine.

Figure 2 is a top plan view of the same.

Figure 3 is a side elevation view showing the means whereby the leaves are fed and carried to the stripping mechanism.

Figure 4 is a side view of the adjustable bearing in connection with my invention.

The machine comprises spindles 4 supported vertically by bearings 5 which bear against the surfaces of the stationary plates 6. The spindles are projected through the bores of the plates 6 and the projected ends 50 of the spindles are threaded to receive the cutters 7. On the spindles 4, between the plates 6 and cutters 7 are mounted rollers 8. Belts 9 are driven adjacent each other between the rollers 8 and guided in alignment 55 with the cutters 7 and the plates 6. A horizontally mounted shaft 10 carries a cutter

11 below the plane of the cutters 7. The shaft 10 carries brushes 12 on opposite sides of the cutter 11.

A shaft 13 is mounted horizontally below 60 and slightly ahead of the shaft 10 and carries a brush 14 registering with the brushes 12. In front of and in position intermediate of shafts 10 and 13 is mounted horizontally a shaft 15 which carries a cylindrical brush 65 16. The shaft 15 is journalled at its opposite ends in an adjustable box 17, supported by a bolt 18 which is threaded to register with the threads of the bore of a nut 20 securely fastened in the pedestal 27. 70

The cutters 7 are beveled to slant downwardly and inwardly and the beveled surfaces are provided with spiral teeth. The cutters 7 are rotated by the spindles 4 in opposite directions in contact with each 75 other at the top, the teeth at the point of contact forming the sides of an isosceles triangle. The cutter 11 is cylindrical and is provided with teeth in contact with the opposite teeth of the cutters 7 thus forming 80 the base of a triangle with the teeth of the cutters 7 as the sides and the point of contact of the cutters as the apex which is adjacent to the carrier belts 9.

From the above description it will be 85 readily understood that tobacco leaves, as 22, carried by the belts 9 causing the butt end or head of the stem to turn downwardly and inwardly and to enter the triangular space bounded by the teeth of the cutters. 90

The cutters 7 will continue to force the stem in the direction in which the leaf is fed by the carrier belts, while the cutter 11 and the brushes on its opposite sides will prevent the laminæ from following the stem and will 95 thus become stripped or separated from the stem and due to the direction of motion of the cutter 11 and its brushes which is opposite that of the belts 9 will carry the stripped laminæ away from the stems and 100 onto the brush 14 which will eventually deposit the laminæ in some receptacle (not shown) in position within the space between the brush 14 and brush 16.

Should a leaf have a broken or loosely 105 hanging butt or head of its stem, it will be intercepted by the brush 16 and carried in a direction away from the stripped leaves, thus preventing the mixing of stripped with unstripped leaves. 110

The brush may be adjusted to be in the proper position to intercept broken leaves

by means of the bolt 18 being turned in the desired direction to either raise or lower the bearing 17 thereby raising or lowering the shaft 15.

5 Having thus described my invention what I claim is:—

10 1. A tobacco leaf stripping machine comprising parallel spindles rotating in opposite directions each carrying in the same plane a disk provided peripherally with stripping teeth, each spindle also carrying a roller adapted to drive a feed belt, a feed belt carried by each roller the belts being adapted to grip a leaf stem between them, 15 and a third stripper disc mounted to rotate on an axis perpendicular to the axes of the parallel spindles and having its stripping edge midway between said spindles in position to engage the leaf carried by the belts. 20 2. A tobacco leaf stripping machine comprising parallel spindles rotating in opposite directions each carrying in the same plane a disc provided peripherally with stripping teeth; each spindle also carrying a roller adapted to drive a feed belt, a feed belt carried by each roller the belts being adapted to grip a leaf stem between them, a third stripper disk mounted to rotate on an axis perpendicular to the axes of the parallel spindles and having its stripping edge midway between said spindles in position to engage the leaf carried by the belts, and means for so rotating the third stripper as to cause the portion of its stripping edge adjacent to the belts to move in a direction opposite to the direction of movement of the belts. 30 35

40 3. A tobacco leaf stripping machine comprising parallel spindles rotating in opposite directions each carrying in the same plane a disk provided peripherally with stripping teeth, each spindle also carrying a roller adapted to drive a feed belt, a feed belt carried by each roller the belts being adapted 45 to grip a leaf stem between them, a third stripper disk mounted to rotate on an axis perpendicular to the axes of the spindles and having its stripping edge midway between the spindles in position to engage the leaf

carried by the belts, means for so rotating the third stripper as to cause the portion of its stripping edge adjacent to the belts to move in a direction opposite to the direction of movement of the belts, and cylindrical brushes one on each side of the third stripper and rotating therewith. 50 55

4. A tobacco leaf stripping machine comprising two adjacent strippers mounted in the same plane and rotating in opposite directions, a stripper mounted to rotate in a plane perpendicular to that of the two strippers, a pair of belts moving over the two strippers in the direction of rotation of said strippers, a pair of rollers guiding the belts centrally above the third stripper, said third stripper rotating in a direction opposite to the direction of movement of the belts. 60 65

5. A tobacco leaf stripping machine comprising two adjacent strippers mounted in the same plane and rotating in opposite directions, a stripper mounted to rotate in a plane perpendicular to that of the two strippers, a pair of belts moving over the two strippers in the direction of rotation of said strippers, a pair of rollers guiding the belts centrally above the third stripper, said third stripper rotating in a direction opposite to the direction of movement of the belts, and means for preventing displacement of the belts relative to each other. 70 75

6. A tobacco leaf stripping machine comprising two adjacent strippers mounted in the same plane and rotating in opposite directions, a stripper mounted to rotate in a plane perpendicular to that of the two strippers, a pair of belts moving over the two strippers in the direction of rotation of said strippers, a pair of rollers guiding the belts centrally above the third stripper, said third stripper rotating in a direction opposite to the direction of movement of the belts, and means for causing the belts to move directly above the two adjacent strippers in a plane parallel with that of said strippers. 80 85 90

In testimony whereof I hereunto affix my signature. 95

FRANK H. AHL.
